CLAIM

The ornamental design for a hinge, as shown and described.

DESCRIPTION

FIG. 1 is a perspective view of a hinge, according to our new design.

FIG. 2 is a front elevational view according to the hinge of FIG. 1.

FIG. 3 is a rear elevational view according to the hinge of FIG. 1.

FIG. 4 is a top plan view according to the hinge of FIG. 1.

FIG. 5 is a bottom plan view according to the hinge of FIG. 1.

FIG. 6 is a first side elevational view according to the hinge of FIG. 1; and,

FIG. 7 is a second side elevational view according to the hinge of FIG. 1.

In the drawings, the dot-dot broken lines illustrate portions of the hinge that forms no part of the claimed design. In FIGS. 1, 6 and 7, the dot-dash-dot lines illustrate openings that form no part of the claimed design.
